(57) **CLAIM**

We claim the ornamental design for a strip of continuous sand paper sheets, as shown and described.

DESCRIPTION

FIG. 1 is a top front perspective view of a strip of continuous sand paper sheets embodying our design;

FIG. 2 is a bottom perspective view of FIG. 1;

FIG. 3 is a top plan view of FIG. 1;

FIG. 4 is a bottom view of FIG. 1;

FIG. 5 is a right side elevational view of FIG. 1;

FIG. 6 is a left side elevational view of FIG. 1; and,

FIG. 7 is a front elevational view of FIG. 1.

The broken line showing the break in the length forms no part of the claimed design.
